UNITED STATES PATENT OFFICE

JOHN N. YOUNESS, OF COLUMBUS, WISCONSIN

HUMIDIFIER

Application filed October 26, 1931. Serial No. 571,159.

This invention relates to improvements in humidifiers adapted for use in dwelling houses and other buildings for distributing water vapor to the various rooms, thereby offsetting the tendency of the air in such rooms to become dry and unhealthful under the influence of the usual heating systems. The usual type of humidifier now in use consists of a water receptacle adapted to be applied to and heated by the steam radiator or other heat distributing element in the heating system but the use of such water pans or receptacles is unsatisfactory because of the necessity of refilling them at frequent intervals and because of their large initial cost arising from the necessity of placing one such pan or receptacle in each room. Attempts have been made to distribute water vapor to rooms through hot air flues leading from the furnace but this method has been unsatisfactory because it is limited to use with hot air furnaces only and because the devices intended for such use have been of limited capacity and have not been capable of automatic operation without refilling.

The principal object of the present invention is to provide an improved humidifier system according to which the humidifier is located in the basement and heated by the furnace with the vapor developed thereby being distributed through the individual rooms of the dwelling or other building independently of the heating system, thus making the invention applicable to furnaces of any type. A further object of the invention is to provide a humidifier adapted to be heated by the flue gases discharged from the furnace and having a large vaporizing capacity so that vapor may be continuously supplied to the various rooms in adequate quantities to maintain the proper degree of moisture in the air. Another object of the invention is to provide a humidifier having a smoke flue passing therethrough and entirely surrounded by the water chamber so that a relatively large vaporizing capacity is obtained as compared with other forms of humidifiers heretofore known. Still another object of the invention is to provide an improved humidifier comprising improved means for maintain-

ing a circulation of air and vapor therethrough and improved means for automatically maintaining a predetermined quantity of water therein. Other objects relate to various features of construction and arrangement which will appear more fully herein-after. 55

The nature of the invention will be understood from the following specification taken with the accompanying drawing, in which one embodiment is illustrated. In the drawing,

Fig. 1 shows a partial vertical section through a dwelling house or other building showing the improved humidifier of the present invention applied to the smoke flue leading from the furnace in the basement and having means for distributing the vapor therefrom to the various rooms; 65

Fig. 2 shows an enlarged longitudinal vertical section through the humidifier illustrated in Fig. 1; and 70

Fig. 3 shows an end elevation of the device illustrated in Fig. 2.

As illustrated in the drawing, the invention is installed in a dwelling house or other building having a basement 10 provided with a floor 11 upon which is mounted the furnace 12 of the heating system by which the building is heated. This furnace may be adapted to heat the building by the distribution of steam or water vapor or hot air but has been represented as a hot air furnace having hot air flues 13 leading therefrom. These flues lead to the various rooms of the building, in the well known manner, but their connections to the rooms have not been illustrated in the drawing. The floor 14 of the first story of the building constitutes the ceiling of the basement and the region above this floor is divided into a number of rooms 15, 16, 17 by the partition walls 18 and 19. The floor 20 of the second story is located in proximity to the ceilings 20^a of the rooms 16 and 17 and another partition 21 divides the space of the second floor into rooms 22 and 23. A chimney 24 extends upwardly from the basement floor 11 and serves to carry the flue gases from the furnace. 85

A smoke flue 25, in the form of a metallic pipe of circular cross-section, leads from the 100

furnace 12 to the chimney 24 and the flue gases passing through this flue 25 are utilized for heating the water in the humidifier and vaporizing it. The humidifier comprises a 5 metallic vessel 26 having a bottom wall 26^a, end walls 26^b, side walls 26^c and a top wall 26^d, forming a closed chamber except for the passages leading thereto and therefrom, as hereinafter described. The end walls 26^b of 10 this vessel are provided near their upper edges with projecting brackets 27 which are welded or otherwise secured thereto and which are adapted to be connected to rods or straps 28 extending upwardly and connected to the stringers 29 of the floor 14 so 15 that the humidifier is suspended from the ceiling of the basement and supported independently of the smoke flue by which it is heated. A smoke flue or conduit 25^a is formed 20 as a part of the vessel 26 and acts as the intermediate portion of the flue 25 leading from the furnace to the chimney. This portion 25^a of the flue which forms a part of the vessel 26 is in the form of an elbow, extending 25 upwardly through the bottom wall 26^a of the vessel as shown at 25^b and then turning angularly toward the right as shown at 25^c, then inclined downwardly at 25^d and finally proceeding horizontally through one of the end 30 walls 26^b as shown at 25^e. This elbow shape of the smoke flue causes the flue gases to follow an irregular path through the humidifier so that they impinge upon the walls of the metallic flue and more thoroughly and efficiently 35 heat the water 30 which occupies the vessel 10 around the flue 25^a. The elbow-shaped portion 25^a of this flue which lies within the vessel has a fluid-tight connection with the walls 26^a and 26^b and projects slightly 40 beyond these walls for connection with the communicating portions of the flue 25. The water 30 in the vessel 26 is supplied through a cold water pipe 31 leading from the supply mains. This pipe may have a manually operated 45 valve 32 connected therein so that the flow of water may be positively shut off when desired, but, during the normal operation of the apparatus, this valve 32 is open and the discharge of water into the vessel 26 is controlled 50 by a float-operated valve 33 which is mounted in one of the end walls 26^b to control the discharge of water through the mouth of the pipe 31. This valve 33 has a stem 33^a which is operated by a lever 33^b pivoted on a bracket 33^c. This lever arm 33^b is connected 55 to a comparatively long arm 33^d upon which is mounted the float 34. When the upper surface 30^a of the water falls below a predetermined level, the valve 33 is opened by 60 the dropping of the float 34 so that additional water is admitted to raise the level in the vessel and thereby close the valve. The level of the water in the vessel is prevented from rising to an undue extent by an overflow pipe 65 35 which leads through one end wall 26^b and

extends downwardly to the drain 36. The float valve is ordinarily adjusted to maintain the normal level of the water in the vessel just below that at which it will flow out through the pipe 35. A drain cock 41 connected in the bottom of the vessel 26 permits the water to be drained off when the valve 32 is closed and the apparatus is not in use. 70

Adjacent the end of the vessel 26 opposite the float valve 33, the vessel is provided with a transverse division wall 37 which is connected to the adjacent end wall 26^b and to the side walls 26^c to form a partition between the water chamber and the passage 38 through which cold air is admitted to the vapor space 39 located above the surface of the water 30. Cold air is admitted to the passage 38 through a pipe 40 which leads upwardly from the region of the floor 11 of the basement and extends through the end wall of the vessel adjacent the bottom of the division wall 37. The air passing into the vessel 26 through the pipe 40 mingles with the vapor in the vapor space 39 arising from the surface of the water 30 which is heated by the flue gases passing through the flue 25^a and this mixture of air and vapor is then carried upwardly through a discharge conduit 42 having communication with the vapor space 39 through the top wall 26^a of the vessel at the end thereof opposite the pipe 40. In this way, a natural draft is created through the humidifier and the vapor is automatically carried upwardly as it is produced by the evaporation of the water. 90

Although the entire vapor supply discharged through the conduit 42 may, if desired, be delivered into a single room of the building, it is ordinarily desirable to connect the conduit 42 to communicate with a plurality of branch conduits 43, 44 and the like, which extend upwardly and deliver vapors upwardly into different rooms of the building. For example, one branch conduit 43 extends upwardly into the partition 18 and delivers vapor through a fitting 45 into the room 15, while the other branch conduit 44 extends upwardly through the partitions 19 and 21 and through the floor 20 and delivers vapor through fittings 46 and 47 into the rooms 16, 17, 22 and 23. In this way, the delivery of vapor to the different rooms of the building is independent of the heat supplied to those rooms and may be made to operate for any room when the heat supply to that room is shut off. 110

It will be apparent that the device of the present invention not only has the advantage of delivering vapor through independent passages to different rooms of a building independently of the supply of heat to those rooms but that it also has the advantage of operating automatically without the necessity of refilling and that it has a large vaporizing capacity due to the novel arrangement of 120 130

the water chamber and the smoke flue in such a way that the flue is entirely surrounded by the water and projects into the water chamber in an irregular manner so that the 5 maximum heat is withdrawn from the flue gases during their passage through the humidifier. The humidifier of the present invention is capable of being constructed at a relatively small cost and it may be readily 10 installed in connection with any furnace to distribute vapor to a variety of places located at various distances from the humidifier proper.

Although one form of the invention has 15 been shown and described by way of illustration, it will be understood that it may be constructed in various other forms within the scope of the appended claims.

I claim:

- 20 1. The combination with a furnace having a smoke flue, of a vessel having a water chamber, a section of said flue passing through said vessel and through said water chamber, said vessel having a vapor space above and open to the water chamber, a vapor conduit 25 communicating with said vapor space, and a cold air pipe having an inlet below the level of said water and discharging into said vapor space below the top of said water chamber.
- 30 2. The combination with a furnace having a smoke flue, of a vessel having a water chamber, an auxiliary smoke flue communicating with said smoke flue at its ends with the inlet thereof located in the bottom of said chamber and the outlet thereof located in one vertical wall of said chamber, said vessel having a vapor space above and open to the water chamber, and a vapor conduit communicating with said vapor space.
- 40 3. The combination with a furnace having a smoke flue, of a vessel having a water chamber, an auxiliary smoke flue communicating with said smoke flue at its ends with the inlet thereof located in the bottom of said chamber and the outlet thereof located in one vertical wall of said chamber, said auxiliary flue having an intermediate portion thereof within said water chamber located at a higher level than its outlet from said chamber, and a vapor conduit communicating with the upper part of said vessel above said water chamber.
- 45 4. The combination in a humidifier, of a vessel, a smoke flue extending through the lower portion of said vessel, said vessel having a water chamber surrounding said smoke flue, means for maintaining a predetermined level of water in said vessel, a division wall extending transversely of said vessel at one 50 end of said water chamber to form a cold air

passage below the top of said water chamber, a cold air pipe communicating with said passage and leading from a point below said vessel, and a vapor conduit communicating with the space above said water chamber at 70 a point removed from said cold air passage.

5. The combination with a furnace having a smoke flue, of a vessel, an auxiliary smoke flue communicating with said smoke flue at its ends with the inlet end thereof extending upwardly through the bottom of said vessel and the outlet end thereof extending through one vertical wall of said vessel with intermediate portions thereof forming an elbow having a part located at a higher level than the outlet of said auxiliary flue from said vessel, said vessel having a water chamber surrounding said auxiliary flue and having a vapor space above and open to said water in said chamber, a vapor conduit communicating with said vapor space, and a cold air conduit leading into said vessel above said auxiliary flue and communicating with said vapor space below the top of said water 80 chamber. 90

6. The combination in a humidifier, of a vessel, a smoke flue extending through the lower portion of said vessel, said vessel having a water chamber surrounding said smoke flue and a vapor space above and open to said water chamber, a division wall inclined upwardly and inwardly from an end wall of said vessel above said smoke flue to form a passage communicating with said vapor space, a vapor conduit communicating with said vapor space, and a cold air inlet pipe communicating with said passage through the end wall of said vessel. 95 100

7. The combination with a furnace having a smoke flue, of a vessel of oblong rectangular horizontal cross-section having the lower portion thereof forming a water chamber, an auxiliary smoke flue in the form of an elbow mounted in said vessel to be surrounded by the water in said chamber, said auxiliary flue having its inlet through the bottom wall of said chamber adjacent one end of said vessel and having its outlet through the end wall of said chamber at the opposite end of said vessel with an intermediate portion thereof at a higher level than said outlet, said vessel having a vapor space in the upper portion thereof above and open to said water chamber, a vapor conduit communicating with said vapor space adjacent one end of said vessel, and a cold air inlet leading through the end wall of said vessel opposite said vapor conduit at a point below the top of said water chamber. 105 110 115 120 125
